G. H. FORSYTH

DISK WHEEL ASSEMBLY

Filed April 3, 1922

Witness:

Geo. C. Dawson

Inventor
George H. Forsyth

UNITED STATES PATENT OFFICE.

GEORGE H. FORSYTH, OF CHICAGO, ILLINOIS.

DISK-WHEEL ASSEMBLY.

Application filed April 3, 1922. Serial No. 549,219.

To all whom it may concern:

Be it known that I, GEORGE H. FORSYTH, a citizen of the United States, residing at Chicago, in the county of Cook and State 5 of Illinois, have invented certain new and useful Improvements in Disk-Wheel Assemblies, of which the following is a specification.

My invention relates to disk wheel construction and has reference particularly to the brake drum, hub and disk assembly.

The objects of the invention are, first, to provide for the ready demounting of the wheel at the hub and affording convenient 15 access to the brake drum and contained mechanism.

Other characteristic features and advantages flowing from the invention will be made apparent hereinafter.

20 To the end that the invention may be readily understood and its advantages appreciated, I have illustrated several embodiments of the same in the accompanying drawing serving as a basis for a somewhat 25 detailed description in this specification.

In the drawings—

Fig. 1 is a fragmentary radial section of a disk wheel adjacent the hub illustrating one embodiment of the invention;

30 Fig. 2 is a front view of a portion of Fig. 1 with certain parts of the disk and front hub plate broken away; and

Fig. 3 is a fragmentary radial section, 35 similar to Fig. 1, showing another embodiment of the invention.

Having particular reference to Figs. 1 and 2 of the drawing, the hub of the wheel is indicated at 11 having front and rear flanges 12 and 13, which may be removable 40 or integral. The disk body of the wheel is indicated at 14 having its central portion at the hub zone lying immediately to the rear of the front hub flange 12 as shown at 15, while outwardly beyond the hub zone the disk is shown as forwardly concave.

Behind the main disk 14 is disposed a disk supporting member 16 bearing against the rear of the disk in its deepest portion. 50 This disk supporting member, adjacent the hub zone, is formed into pocket portions 16^a and 16^b which are offset to the front and rear, the front portions continuing inwardly in bearing contact with the disk and opposite the front hub flange 12, and thence again rearwardly and inwardly to an abut-

ment against the front face of the rear flange 13 at the hub. Thus the portions 16^b of the disk supporting member extend rearwardly from the point of offset and lie 60 against the front face of the fixed flange 13. The portions 16^b are fixedly secured to the rear hub flange 13 by means of short bolts 17 while longer attaching bolts 18 transfix the fixed hub flange 13, the disk 65 supporting portions 16^a and 16^b, the disk portion 15 and the removable hub flange 12, all of these parts being firmly clamped together by means of the nuts 19 acting upon said attaching bolts. It will be observed 70 that the torque of the hub 11 is transmitted directly to the member 16 by means of the portions 16^b through the bolts 17, and is then transferred from the portions 16^a of the member 16 to the disk proper of the 75 wheel through the connection of 16^a and 15 by the bolts 18.

In the case of the rear wheel the disk supporting member 16 forms the front wall of the brake drum 20 which contains the brake 80 adjusting mechanism, a portion of which is indicated at 21. The concentrically disposed brake bands are indicated at 22 and 23 with their friction liners 22^a and 23^a acting upon the double coned periphery 24 of the drum. 85

The front wall 16 of the brake drum is provided with a manhole 25 at a position to get ready access to the brake mechanism within the drum. This opening 25 is normally closed by the wheel disk when 90 the same is in its assembled relation to the hub, but to afford access to the drum interior it is only necessary to demount the wheel at the hub by removing the nuts 19 and the flange 12 thereby uncovering the opening 25. 95

In Fig. 3 of the drawing, a form of construction is illustrated which includes a two-part hub comprising the demountable portion 26 and the fixed portion 27 having integral radially fluted portions at 28 which 100 provide a driving interlock between the two, thus taking the shear from the bolts 29 which transfix the rear hub flange 30 and the front hub flange 31. The hub portion 27 has a radial extension 32 which forms a 105 filler or spacing member between the portion 15 of the disk and the hub flange 30. Here the brake drum is shown as a cylindrical member 33 closed at the front by a flat wall having an opening formed by the 110 rear hub flange 30 and having an opening 34 therein. Bushings 35 and 36 about the

bolts 29 give an enlarged contact area between the bolts on the one hand and the hub flanges and disk on the other.

The demounting at the hub of the wheel assembly shown in Fig. 3 gives access through the opening 34 to the brake drum interior as in the former case.

I claim:

1. In a disk wheel, the combination with the hub, of a disk demountably secured thereon, and a brake drum also secured to the hub at the rear of the disk and having a front opening normally obstructed by the disk when on the hub and through which access may be had to the interior brake mechanism when the disk is demounted.

2. In a disk wheel, the combination with a hub, of a disk demountably secured thereon, and a brake drum also secured to the hub at the rear of the disk and having an opening in its front wall which opening is normally closed by the disk when on the hub and through which access may be had to the interior brake mechanism when the disk is demounted.

3. In a disk wheel, the combination of a hub having front and rear flanges spaced apart, a disk body disposed in the hub zone at the rear of the front flange, and a disk-supporting member bearing on the rear of the disk outwardly of the hub zone and having portions laterally offset towards the front and rear within the hub zone and bearing respectively one against the rear of the disk opposite the front flange and the other against the front of the rear flange, and attaching bolts transfixing the two flanges and the interposed disk and certain of the offset portions of the supporting member.

4. In a disk wheel, the combination of a hub having front and rear flanges spaced apart, a disk body disposed in the hub zone at the rear of the front flange, and a disk-supporting member bearing on the rear of the disk outwardly of the hub zone and having portions laterally offset towards the front and rear within the hub zone and bearing respectively one against the rear of

the disk opposite the front flange and the other against the front of the rear flange, bolts securing the last mentioned portions to the rear flange, and attaching bolts transfixing the two flanges and the interposed disk and forwardly offset portions of the supporting member.

5. In a disk wheel, the combination of a hub having front and rear flanges spaced apart, a disk body disposed in the hub zone at the rear of the front flange, and a brake drum having its front wall formed as a disk-supporting member bearing on the rear of the disk outwardly of the hub zone and having portions laterally offset towards the front and rear within the hub zone and bearing respectively one against the rear of the disk opposite the front flange and the other against the front of the rear flange, bolts securing the last mentioned portions to the rear flange, and attaching bolts transfixing the two flanges and the interposed disk and forwardly offset portions of the supporting member.

6. In a disk wheel, the combination of a hub having front and rear flanges spaced apart, a disk body disposed in the hub zone at the rear of the front flange, and a brake drum having its front wall formed as a disk-supporting member bearing on the rear of the disk outwardly of the hub zone and having portions laterally offset towards the front and rear within the hub zone and bearing respectively one against the rear of the disk opposite the front flange and the other against the front of the rear flange, bolts securing the last mentioned portions to the rear flange, and attaching bolts transfixing the two flanges and the interposed disk and forwardly offset portions of the supporting member, the brake drum having an opening in its front wall normally closed by the disk when on the hub and through which access may be had to the interior brake mechanism when the attaching bolts are released and the disk is demounted.

In testimony whereof I have hereunto subscribed my name.

GEORGE H. FORSYTH.
